DESIGN FOR A LIP PROTECTOR FOR DRINKING VESSELS

Mildred L. Hall, Meriden, Conn.

Application September 20, 1938, Serial No. 79,996

Term of patent 14 years

To all whom it may concern:

Be it known that I, Mildred L. Hall, a citizen of the United States, residing at Meriden, in the county of New Haven and State of Connecticut, have invented a new, original, and ornamental Design for a Lip Protector for Drinking Vessels, of which the following is a specification, reference being had to the accompanying drawing, forming part thereof, in which—

Fig. 1 is a front view in elevation of a lip protector for drinking vessels, showing my design;

Fig. 2 is a top plan view of the lip protector shown in Fig. 1;

Fig. 3 is an edge view of the lip protector shown in Fig. 1 as viewed from the right.

I claim:

The ornamental design for a lip protector for drinking vessels, as shown.

MILDRED L. HALL.
